REFRIGERATING APPARATUS

Daniel D. Wile, Detroit, Mich., assignor to Detroit Lubricator Company, Detroit, Mich., a corporation of Michigan

Application February 17, 1933, Serial No. 657,169

8 Claims. (Cl. 62—101)

My invention relates to new and useful improvements in refrigerating apparatus, and more particularly to an apparatus having a continuous liquid circulating system.

An object of my invention is to provide means for controlling the circulation of a liquid refrigerant medium through the system.

Another object is to provide a system by which the temperature within the region or space to be cooled may be readily controlled.

Another object is to provide an apparatus which is of simple construction and which will be efficient in operation.

The invention consists in the improved construction and combination of parts, to be more fully described hereinafter, and the novelty of which will be particularly pointed out and distinctly claimed.

In the accompanying drawings, to be taken as a part of this specification, I have fully and clearly illustrated a preferred embodiment of my invention, in which drawings—

Figure 1 is a top plan view of a box or container but with certain cover plates or members removed, and which embodies the apparatus of my invention;

Fig. 2 is a top plan view of the box of Figure 1 but with the top closure wall removed to show internal construction, and having certain parts of the heat insulating material broken away;

Fig. 3 is a view in section on the line 3—3 of Fig. 2, also having portions of the heat insulating material broken away, and

Fig. 4 is an enlarged detail view in longitudinal central section of a control device forming a part of my apparatus.

Referring to the drawings by characters of reference, 1 designates, generally, a box or container having a bottom wall 2 from which rise side or end walls 3, 4, and front and rear walls 5, 6. The walls of the container are heavily insulated with a heat insulating medium 7 which may be of any of the well-known materials which will substantially prevent transfer of heat to the interior of the box 1 from the surrounding atmosphere. The inner walls of the box 1 are provided with a metal liner which serves to retain the insulating material in position. The liner comprises a bottom wall 8 from which rise side or end walls 9, 10, and front and rear walls 11, 12. The side walls 3, 4 and the front and rear walls 5, 6 terminate at their top edges in a plurality of steps or shoulders 13. The vertical liner walls terminate at their top edges in a substantially horizontal continuous flange 14 which is turned outwardly and seats

upon the horizontal face of the innermost of the steps 13. The box 1 is provided with a top wall 15 which is lined on its inner face with a metal plate 16 which seats at its marginal edges upon the flange 14. The top wall 15 is provided with a thick layer of heat insulating material similar to the remaining walls of the box, and has its surrounding edges stepped or shouldered to conform to the steps 13 so as to tightly seal the interior of the box 1. Within the box 1 there is an open-topped casing 17, preferably positioned centrally within the interior of the box and providing a refrigerant medium receiving chamber. The casing 17 has a bottom wall 18 which seats upon and is supported by heat insulating material 19 resting on the bottom liner wall 8. The casing 17 has side walls 20, 21, and front and rear walls 22, 23 which are joined to each other and to the bottom wall 18 from which they rise substantially vertically. The walls 20, 21, 22, and 23 terminate substantially at and preferably slightly spaced from the top wall liner member 16. The interior of the box 1 may be provided with vertical partitions or walls 24, 25 extending between the front and rear liner walls 11, 12 at the sides of the casing 17, and also extending from the bottom liner wall 8 to the liner of the top wall 15. These partitions provide compartments or chambers 26, 27 within the box 1, which are to be cooled or refrigerated.

Positioned in the upper portion of the interior of the box 1, and preferably between the casing wall 22 and the front liner wall 11, there is a control device 28. The device 28 preferably comprises a chambered element or casing member having a substantially cylindrical side wall 29 closed at one end by a bottom wall 30 and at its other end by a top wall 31. Through the bottom wall 30 there is an inlet port 32 which opens into the bore 33 of a sleeve member or hollow boss 34 positioned within the chamber 35 of the device 28 and rising from the bottom wall 30 thereof. The bore 33 receives the lower end of a reciprocable tubular member 36 which has a sliding fit within the bore 33. Through the wall of the tubular member 36 there are one or more apertures 37 positioned above the sleeve member 34, and which serve to establish communication between the inlet 32 and the chamber 35. The bottom edge 38 of the aperture 37 defines the overflow level from the inlet 32 into the chamber 35 and determines the cut-off point for liquid circulation in the system. The chamber 35 is provided with one or more outlet ports 39, preferably two in number, through the side wall 28 55

and positioned oppositely to each other adjacent the bottom of the chamber 35. The upper end of the tubular member 36 is secured to the lower end of an internally threaded sleeve member 40 which is vertically reciprocable in a bonnet or cap member 41 screw-threaded, or otherwise secured, in an aperture 42 through the top wall 31. The sleeve member 40 and the cap member 41 are preferably provided with cooperating longitudinal ribs or guide grooves 42a, 43 respectively, which serve to prevent rotation of the sleeve member 40. Within the sleeve member 40 there is a screw 44 having threaded engagement with the internal threads in the member 40. The screw 44 is carried by an operating member or stem 45 which is screw-threaded, as at 46, within the cap member 41. A substantially cylindrical extension 47 on the cap member 41 surrounds the stem 45 and provides a packing material receiving recess. Within the recess provided by the extension 47 there is suitable packing material 48 held under compression by a helical coil spring 49 surrounding the stem 45 and seating against a cap 50 screw-threaded, or otherwise secured, upon the extension 47. The stem 45 extends through an aperture in the cap 50 and is provided with an external polygonal portion 51 by which the screw 44 may be rotated to thereby raise or lower the tubular overflow controlling member 36. The extension 47 preferably projects into an aperture 52 through the top wall 15 so that access may be had to the operating member 45.

The top wall 15 is provided with one or more apertures 53 therethrough and which open into the compartment 26 so that access may be had thereto. The apertures 53 are normally closed by cover plates 54. The compartment 27 is accessible through the top wall 15 by means of apertures 55 which are normally closed by cover plates 56. The interior of the casing 17 registers with an opening 57 through the top wall 15, the opening being normally closed by a cover plate 58.

The outlet ports 39 are connected, as at 59, to tubular conduit members 60, 61 which extend through the compartments 26, 27 respectively. The conduit member 60 has a downflow leg or portion 62 which is in intimate heat transfer relation with the side wall 20 of the casing 17, 60 preferably being soldered thereto. The portion 62 extends to the rear liner wall 12. At the rear liner wall 12 the member 60 is turned toward the end wall 8 to provide a conduit portion 63. The juncture between the portions 62 and 63 defines 65 the low point of the system with the portion 63 rising at a slight inclination toward the wall 8. At the wall 8 the member 60 is turned to provide a portion 64 lying against the liner wall 8 and extending at substantially the upward inclination of the portion 63 to the front liner wall 11. At the wall 11 the member 60 is turned to provide a portion 65 which lies thereagainst and extends at the upward inclination of the portions 63 and 64 to a point substantially at the 70 midportion of the wall 11. The portion 65 terminates in an inturned conduit portion 66 which forms the other end portion of the conduit member 60 and which opens into one branch or arm of a T fitting 67 to which it is secured by a sleeve nut 68. The fitting 67 is threaded or otherwise secured and sealed in the inlet 32. The portions 63, 64, and 65 are preferably soldered to the liner walls 12, 8, and 11 respectively, so that the liner walls provide an extended heat 75 absorbing surface for these portions which de-

fine the upflow leg of the system. The conduit member 60 is preferably of copper and is substantially semi-circular in cross section, the flat face of the conduit member engaging the casing wall 20 and also the liner walls. The tubular 5 conduit member 61 also provides a downflow and an upflow leg for the compartment 27, and since it is substantially identical in all respects with the conduit member 60, the primes of the reference characters applied to the conduit member 60 designate like parts of the member 61. The casing 17 is preferably surrounded by heat insulating material 69 which may be retained in position by the partitions 24, 25 and by the front and rear liner walls 11, 12. The device 28 and 15 the conduit portions 62, 62' are preferably surrounded by and embedded in the material 69.

The operation of my apparatus and of the circulatory systems defined by the conduit members 60 and 61 together with the control device 28 is 20 as follows: The conduit members 60 and 61 are filled with an expansible-contractible liquid, such as alcohol, which will vary in volume in accordance with the heat content thereof. When the systems are at rest and at substantially room 25 temperature, the level of the liquid will be at the line L—L in the chamber 35. The apparatus is placed in operation by placing a refrigerant medium, such as carbon dioxide ice, within the casing 17. The carbon dioxide ice within the casing 17 will reduce the temperature therein and of the walls of the casing, thereby abstracting heat from the liquid in the conduit portions 62 and 62'. Abstraction of heat from the liquid will increase 30 its density and start circulation of the liquid 35 through the conduit members 60 and 61 in the direction indicated by the arrows. The cooled liquid flowing into the compartments 26 and 27 will absorb or abstract heat from the compartments which will be materially increased in 40 efficiency due to contact of the conduit members with the liner walls. As the liquid continues to circulate with heat being abstracted at the casing 17 by the refrigerant medium therein, the temperature within the compartments 26 and 27 45 will decrease, and as the temperature within the compartments 26 and 27 decreases, the heat content of the circulating liquid will also decrease. Since the volume of the liquid varies in accordance with its heat content, the liquid will contract 50 thereby decreasing its volume and lowering the level of the liquid in the chamber 35 below the line L—L. The temperature of the circulating liquid will continue to decrease and the volume thereof will ultimately contract to a point at 55 which the liquid level in the chamber 35 will be below the level of the overflow edge 38. This will result in the liquid circuit being broken and will stop further circulation of the liquid through the compartments 26 and 27. With the liquid in the 60 conduit members 60 and 61 at rest, abstraction of heat from chambers 26 and 27 will cease. If the temperature in the compartments 26, 27 should now increase for any reason, the liquid in the portions of the conduit members within the compartments 26 and 27 will expand and raise the liquid level in the chamber 35 above the overflow edge 38, which will again set up circulation of the liquid through the systems. The temperature within the compartments 26 and 27 may be 65 controlled by adjustment of the overflow edge 38 by raising or lowering the tubular member 36. Downward movement of the edge 38 from the position shown in Fig. 4 will result in a lower 70 temperature in the chambers 26 and 27 because 75

the liquid in the circulating systems will have to contract to a greater extent in order to decrease the volume below this lower position of the overflow edge 38. In order for the liquid to contract further, the temperature of the liquid must be decreased but this can only be accomplished by a further removal of heat from and a lowering of the temperature in the compartments 26 and 27 by the circulating liquid.

10. What I claim and desire to secure by Letters Patent of the United States is:

1. A refrigeration apparatus comprising a circulatory system defined by an endless duct, means to abstract heat from one portion of said system, said system having another portion in heat absorbing relation to a region to be cooled, an expansible and contractible liquid in said system adapted to circulate due to difference in temperature between said portions, said liquid normally filling said system to a level to establish a continuous liquid circuit and having its volume variable in accordance with its heat content, said duct including a chamber having an inlet and an outlet, and an adjustable baffle member interposed between said inlet and said outlet and providing an elevated overflow portion in said duct, said baffle member being adjustable in height to regulate the temperature to be maintained in the region to be cooled.

10. 2. A refrigeration apparatus comprising a circulatory system, means to abstract heat from one portion of said system, said system having another portion in heat absorbing relation to a region to be cooled, an expansible and contractible liquid in said system adapted to circulate due to difference in temperature between said portions, said liquid normally filling said system to a level to establish a continuous liquid circuit and having its volume variable in accordance with its heat content, said system including a chamber having inlet and outlet ports, and an adjustable tubular member in said chamber and having a sliding fit in one of said ports, said tubular member having an overflow edge portion operable to interrupt the liquid circuit upon contraction of the liquid.

3. A refrigeration apparatus comprising a container enclosing a space to be refrigerated, a casing within said container and adapted to receive a refrigerant medium, a conduit member having one portion thereof in intimate heat exchange relation to said casing and having another portion in intimate heat exchange relation with the interior of said container, a chambered element having an inlet and an outlet, said conduit having one end connected to said inlet and having its other end connected to said outlet, an expansible-contractible liquid in said conduit and chambered element, said liquid normally filling said conduit and chambered element to a level to establish a continuous liquid circuit, adjustable overflow means in said chambered element operable upon contraction of said liquid to interrupt flow between said inlet and said outlet, and means to adjust said last-named means.

4. A refrigeration apparatus comprising a container enclosing a space to be refrigerated, a casing within said container and adapted to receive a refrigerant medium, a conduit member having one portion thereof in intimate heat exchange relation to said casing and having another portion in intimate heat exchange relation with the interior of said container, means insulating said casing and said one conduit portion from the in-

terior of said container, a chambered element having an inlet and an outlet, said conduit having one end connected to said inlet and having its other end connected to said outlet, an expansible-contractible liquid in said conduit and chambered element, said liquid normally filling said conduit and chambered element to a level to establish a continuous liquid circuit, adjustable overflow means in said chambered element permitting communication between said inlet and said outlet but effective to interrupt liquid flow between said inlet and said outlet, and means to adjust said last-named means.

5. A refrigeration apparatus comprising a circulatory system defined by an endless duct, means to abstract heat from one portion of said system, said system having another portion in heat absorbing relation to a region to be cooled, an expansible and contractible liquid in said system adapted to circulate due to difference in temperature between said portions, said liquid normally filling said system to a level to establish a continuous liquid circuit and having its volume variable in accordance with its heat content, a movably supported tubular member in and forming part of said duct and through which the liquid flows, said tubular member providing an elevated portion in said system over which the liquid flows, and means to raise and lower said tubular member to regulate the height of the elevated portion to control the extent of contraction of the liquid volume which will interrupt the liquid circuit.

6. A refrigeration apparatus comprising a circulatory system, means to abstract heat from one portion of said system, said system having another portion in heat absorbing relation to a region to be cooled, an expansible and contractible liquid in said system adapted to circulate due to difference in temperature between said portions, said liquid normally filling said system to a level to establish a continuous liquid circuit and having its volume variable in accordance with its heat content, said system including a chamber having inlet and outlet ports, a tubular member movably supported in said chambered element and extending upward from one of said ports, said tubular member having an overflow edge portion, and means to raise and lower said tubular member to regulate the extent of contraction of said liquid which will interrupt the liquid circuit.

7. In a refrigeration apparatus, a control device including a casing having an inlet port and an outlet port for flow through said casing of a heat transferring liquid, a movably supported tubular member extending upward into said casing from one of said ports and having an overflow edge portion operable to control the circulation through said casing of the heat transferring liquid, adjustment means projecting into said casing for raising and lowering said tubular member, and means operatively connecting said adjustment means and said tubular member.

8. In a refrigeration apparatus, a control device including a casing having an inlet port and an outlet port for flow through said casing of a heat transferring liquid, a movably supported tubular means extending upward into said casing from one of said ports and having an overflow edge portion operable to control the circulation through said casing of the heat transferring liquid, and means for adjusting the height of said overflow edge.
